UNITED STATES PATENT OFFICE.

ARCHIBALD EDWIN RHOADES, OF ELK GROVE, CALIFORNIA.

BALE-TIE MACHINE.

No. 819,925.

Specification of Letters Patent.

Patented May 8, 1906.

Application filed November 6, 1905. Serial No. 286,071.

To all whom it may concern:

Be it known that I, ARCHIBALD EDWIN RHOADES, a citizen of the United States, residing at Elk Grove, in the county of Sacramento and State of California, have invented 5 a new and useful Bale-Tie Machine, of which the following is a specification.

This invention relates to machines for twisting loops in wire strands, and is primarily intended for use in the manufacture of wire bale-ties.

It is proposed to provide for twisting, stretching, and cutting the wire into lengths by the manipulation of a single controlling 15 device and to have the operations automatically follow one another in the order enumerated.

With these and other objects in view the present invention consists in the combination 20 and arrangement of parts, as will be hereinafter more fully described, shown in the accompanying drawings, and particularly pointed out in the appended claims, it being understood that changes in the form, proportion, size, and minor details may be made 25 within the scope of the claims without departing from the spirit or sacrificing any of the advantages of the invention.

In the drawings, Figure 1 is a side elevation of the machine of the present invention in the initial position of its operation. Fig. 2 is a plan view thereof in the final stages of its operation. Fig. 3 is an elevation looking at the other side of the machine at the end of 35 the operation thereof. Fig. 4 is a cross-sectional view on the line 4-4 of Fig. 3. Fig. 5 is an enlarged detail sectional view of the cutting device. Fig. 6 is a detail perspective view of the knife for cutting the wire. Fig. 7 40 is a detail perspective view of the cam-knife lever for actuating the cutting device. Fig. 8 is a cross-sectional view on the line 8-8 of Fig. 5. Fig. 9 is a detail view of the product of the machine.

Like characters of reference designate corresponding parts in all of the figures of the drawings.

The present machine includes a metallic bed 1 of suitable proportions and having 50 overhanging longitudinal flanges 2, constituting a guideway for the flat base member 3, which is somewhat shorter than the bed and is mounted to slide longitudinally thereon. At each end of the bed there is an opening 55 for the reception of a fastening 4 to secure the machine to the top of a suitable support 5,

preferably in the nature of a work-table and considerably longer than the machine. A longitudinal stiffening-web 6 rises from the base 3, and rear and intermediate posts 7 and 8 rise from the web and constitute bearings for a rotatable mandrel 9, which is provided with one or more spiral grooves or guideways 10, located between the bearing-posts. The front end of the mandrel is extended in front 65 of the post 8 and provided with a hook 11.

For the purpose of rotating the mandrel there is a lever 12 fulcrumed upon the front of the bed, as shown at 13. Upon the mandrel 9 there is a slide 14, which is provided 70 with one or more internal projections 15, slidably engaging the spiral guideways 10. A yoke 16 straddles and is connected to the slide 14, and a connecting-rod 17 connects the yoke and the lever 12. By moving the 75 lever the slide may be worked back and forth upon the mandrel and the latter rotated by reason of the projections 15, working in its spiral guideways.

It is proposed to have the base of the machine stationary during the rotation of the mandrel, and this is accomplished by the means best shown in Fig. 3 of the drawings. A bell-crank lever 18 is fulcrumed upon the rear post 7 and has its upright arm provided 80 with a ring or eye 19, loosely embracing the mandrel and in the path of the slide 14. The lower arm of the bell-crank lever is slotted or bifurcated, as to 20, for the reception of a pin 21, projecting laterally from a rod 22, which 85 has its forward end pivotally supported upon the post 8, as shown at 23. The rear end of the rod 22 is provided with a downwardly-extending projection 24, which normally lies in an opening 25, formed in the base 3, said 90 projection being adapted to engage an opening 26 in the bed when the slide is at its forward limit, so as to hold the slide against rearward movement during a certain portion 95 of the movement of the lever 12. During 100 the rearward swing of the lever 12 the slide 14 moves rearwardly upon the mandrel until it strikes the bell-crank lever 18 and swings the latter to lift the projection 24 out of the seat 26 in the bed, whereby the base is freed from 105 the bed and will slide rearwardly during further movement of the lever 12 until the latter strikes the pivotal connection between the slide 14 and the connecting-rod 17 as a stop to limit further rearward movement of the 110 base.

In front of the intermediate post 8 there is

a front post 27, rising from the base, and in the rear side of this post there is an upright guideway 28 for the reception of a knife-blade 29. The upper end of this knife-blade 5 is beveled to form a cutting edge 30, and from what will be termed the "inner edge" of the blade there rises a guide projection or prong 31. Below the cutting edge 30 of the knife-blade there is a seat or notch 32 formed 10 in the inner edge of the body of the blade. A bearing-ear 33 extends rearwardly from the post and supports a handled cam 34, which is pivoted thereon by a suitable pivot 35 and has a nose or projection 36, engaging the seat 15 or notch 32 of the knife-blade. The handle 37 of the cam extends downwardly and is received within alined slots 38 and 39 in the base and bed, respectively. During the final 20 stage of movement of the base the handle 37 will engage the rear end of the slot 39, which will result in turning the cam 34 and elevating the knife-blade 29 so as to slide its cutting edge 30 across a transverse notch or seat 40, formed in the upper portion of the post 25 for the purpose of cutting a wire.

In practice one end of a length of wire 41 is manually twisted to form a loop 42, which is then engaged with a hook or projection 43, carried by the forward end of the support or 30 work-table 5. The wire is then passed rearwardly between the top of the post 27 and the guard 31, care being taken to enter the wire into the wire-receiving seat 40 of the post, after which the wire is engaged with the hook 11 and then drawn forwardly against the beveled outer edge portion 44 of the post and held in the left hand of the operator while the lever 12 is being forced rearwardly by the right hand. It will of course be understood that the base of the machine is first 35 moved to its forward limit with the locking-bolt 24 engaged with the seat 26 of the bed, so as to prevent rearward movement of the base during the initial rearward movement of the lever 12. During the first portion of the rearward movement of the lever the mandrel 9 is of course rotated, whereby the hook 11 is also rotated and a loop is twisted in the wire, as shown at 45. When the slide 14 strikes 40 the upper arm of the bell-crank lever 18, the bolt 24 is lifted from the bed and further movement of the lever slides the base rearwardly without rotation of the mandrel, thereby to stretch the wire portion 41 and take 45 out all bends and kinks therein. While the base is sliding rearwardly, the cam-lever 34 is inactive as it moves rearwardly with the base through the slot 39 of the bed until it contacts with the rear end of the slot, whereupon further rearward movement of the base 50 will rock the lever, and thereby elevate the knife-blade 29, which severs the wire portion 41 and leaves the loop 45 upon the wire portion 43, which is held in the left hand of the 55 operator. By the foregoing operation the

wire portion 41 is formed into a bale-tie of the desired length with the loop 42 at one end thereof. After the wire has been cut the portion 41 is disengaged from the hook 43, and the loop 45 is then engaged with the hook 43 70 and the wire portion 46 engaged with the wire-receiving seat 40 and the hook 11 in the manner hereinbefore described, the base of course having been moved forwardly to its limit. The lever 12 is then swung rearwardly 75 and the operation of the machine repeated to form another bale-tie.

In setting up the machine it is of course located at a distance from the hook or projection 43 in accordance with the desired 80 length for the bale-ties, whereby each tie will be stretched and then cut off at the desired length.

From the foregoing description it will be understood that the several successive operations of the present machine are entirely automatic, and the machine requires no attention beyond the manipulation of the lever 12. Furthermore, all the parts are compactly assembled and are conveniently accessible for repairs. 85

Having thus described the invention, what is claimed is—

1. A machine of the class described including a slide, wire-twisting means carried 95 by the slide, wire-cutting means carried by the slide, means for operating the twisting means and then moving the slide to stretch the wire, and a trip in the path of the wire-cutter to actuate the latter by the movement 100 of the slide.

2. In a machine of the class described, the combination with a bed, of a slide mounted thereon, a rotatable mandrel mounted upon the slide and having a wire-engaging element 105 and a spiral guideway, a sleeve slidably embracing the mandrel and engaging the guideway thereof, means to move the sleeve upon the mandrel to rotate the latter and then move the slide, and means to interlock the slide with the bed and provided with a trip portion in the path of the sleeve to release the slide from the bed. 110

3. In a machine of the class described, the combination with a bed having a seat, of a 115 base mounted to slide upon the bed, a mandrel rotatably mounted upon the base and provided with a spiral guideway and a wire-engaging element, a slide working upon the mandrel and engaging the guideway thereof, means to move the slide upon the mandrel, a latch carried by the base for engagement with the seat of the bed, and a trip-lever mounted upon the base and connected to the latch, a portion of the lever lying in the path 120 of the slide to release the latch. 125

4. In a machine of the class described, the combination with a bed having a seat, of a base slidable upon the bed, a rotatable mandrel carried by the base and provided with a 130

5 spiral guideway and a wire-engaging element, a slide working upon the mandrel and engaging the spiral guideway, means for moving the slide upon the mandrel, a rod 10 pivotally supported upon the base and having a latch portion to engage the seat of the bed, and a bell-crank lever connected to the rod and provided with an eye loosely embracing the mandrel and disposed in the 15 path of the slide for releasing the latch from the bed.

15 5. In a machine of the class described, the combination with a bed, of a base slidable thereon, twisting means carried by the base, means to slide the base upon the bed, a wire-cutter carried by the base and including a 20 controlling-lever, and a stop provided upon the bed in the path of the lever to actuate the cutter.

20 6. In a machine of the class described, the combination with a bed, of a base slidable thereon, twisting means carried by the base, means to slide the base upon the bed, and a 25 wire-cutter carried by the base and including a lever, the base and the bed being provided with openings receiving the lever, and the rear end of the opening in the bed lying in the path of the lever to swing the latter and operate the wire-cutter.

7. In a machine of the class described, the 30 combination with a bed having a seat, of a base slidable thereon, a rotatable mandrel carried by the base and provided with a wire-engaging element and a spiral guideway, a 35 slide embracing the mandrel and engaging the spiral guideway, a lever fulcrumed upon the bed, a connecting-rod between the lever and the slide, a swinging latch carried by the base for engagement with the seat of the bed, a bell-crank lever connected to the latch and 40 having a portion lying in the path of the slide, a wire-receiving seat provided upon the base in front of the mandrel, a vertically-movable cutting-blade working across the seat, and a bell-crank lever fulcrumed upon 45 the base and engaged with the knife-blade for elevating the same, the base and the bed having openings receiving the lever, the rear end of the opening in the bed lying in the rearward path of the lever to engage and operate the same for elevating the knife-blade.

In testimony that I claim the foregoing as my own I have hereto affixed my signature in the presence of two witnesses.

ARCH. EDWIN RHOADES.
